UNITED STATES PATENT OFFICE.

EDGAR CHARLES SELLECK, OF SAN FRANCISCO, CALIFORNIA.

TROLLING-SPOON.

1,400,629.

Specification of Letters Patent. Patented Dec. 20, 1921.

Application filed February 19, 1920. Serial No. 359,792.

To all whom it may concern:

Be it known that I, EDGAR C. SELLECK, a citizen of the United States, and a resident of San Francisco, in the county of San Francisco and State of California, have invented certain new and useful Improvements in Trolling-Spoons, of which the following is a specification.

My invention is an improvement in trolling spoons, and has for its object to provide a spoon or spinner of the character described, which may be easily and cheaply manufactured, and which will be attractive to the fish.

15 In the drawings:

Figure 1 is a top plan view of the improved spoon,

Fig. 2 is a similar view of the connector for connecting the hook, the line and the 20 spoon,

Fig. 3 is a transverse section on the line 3—3 of Fig. 1.

In the present embodiment of the invention the spoon 1 is of oval formation, and 25 concavo-convex, and suitably painted or plated in colors or the like to attract the fish. This spoon may be nickelized, silvered, porcelainized or painted as may be desired, and it is connected with a shank or link 30 formed from wire bent to shape.

This shank is composed of a body portion 2 having at one end a loop 3, and at the other an eye 4, the shank being provided adjacent to the eye with a laterally extending loop 5. The loop 3 is adapted for connection with a hook or hooks indicated at 35 6, and the eye 4 is adapted for connection with a suitable swivel indicated at 7, for connecting the line to the shank.

40 The spoon 1 has an opening 8 through which the loop 5 is passed, to connect the spoon to the shank, and the body 2 of the shank is wrapped with silk thread indicated at 9 or the like, of a brilliant color, as for

instance vermillion, red, or shades of the 45 same. A bead 10 is mounted on the shank between the wrapping 9 of thread and the laterally extending loop 5, and the spoon is ready for use.

The improved spoon is used in the usual 50 manner, and the winding of fabric which may be of silk or other material, represents the body of the insect, the bead representing the head. Referring to Fig. 2, it will be seen that the shank is formed by bending a length of wire in such manner that the shank is composed of two strands of wire lying along one side of each other, and with the ends of the wire at the center of one of the strands.

It will be noticed referring to Fig. 2, that the extremities of the wire from which the shank is formed, lie upon the opposite side of the central portion thereof from the laterally extending loop 5, so that the lower 65 member of the said loop crosses the central portion of the wire. Thus there is provided a straight pull for the spoon when trolling, and in practice the extremities will be soldered or brazed to the central portion 70 of the wire, that is, the shank and the two strands of the shank will be soldered together.

I claim:

A trolling spoon, comprising a shank 75 formed from a single piece of wire doubled upon itself to form a shank consisting of two members lying alongside each other, the ends of the wire being intermediate the end of one of the said members, said wire having at one end a loop and at the other an eye, and having adjacent to the eye an outwardly bent portion forming a loop, a spoon supported by said last named loop, a swivel supported by the eye, and hooks supported 80 by the first named loop.

EDGAR CHARLES SELLECK.
